CLAIM

I claim the ornamental design for a connection disc for a racquet sport ball, as shown and described.

DESCRIPTION

FIG. 1 is a side view of the connection disc for a racquet sport ball showing my new design;

FIG. 2 is a top view thereof;

FIG. 3 is a perspective view thereof;

FIG. 4 is a bottom view thereof;

FIG. 5 is the opposite side view of FIG. 1;

FIG. 6 is an end view thereof; and,

FIG. 7 is the opposite end view of FIG. 6.
